UNITED STATES PATENT OFFICE

HENRY F. H. BOTHE, OF NORTH ATTLEBOROUGH, MASSACHUSETTS.

DESIGN FOR A VINAIGRETTE.

SPECIFICATION forming part of Design No. 15,611, dated December 16, 1884.

Application filed September 22, 1884. Term of patent 7 years.

To all whom it may concern:

Be it known that I, HENRY F. H. BOTHE, a subject of the Emperor of Germany, residing at North Attleborough, in the county of 5 Bristol and State of Massachusetts, have invented a new and useful Design for Metallic Vinaigrettes; and I do declare the following to be a full, clear, and exact description of the design, reference being had to the accompanying drawing, and to letters or figures of reference marked thereon, which form a part of this specification.

The figure of the drawing is a representation of this invention, and is a perspective view.

15 This design has relation to vinaigrettes or perfume-bottles; and it consists in the novel form and configuration, as hereinafter shown and described.

20 In the accompanying drawing, the letter *a* |

designates the bottle, and *b* the stopper. The stopper *b* is in the expanded or bulged form of the upper portion of a cork which has been bound to the mouth of a bottle containing champagne, having the appearance of a corded binding. 25

Having described this design, what I claim, and desire to secure by Letters Patent, is—

The design for a vinaigrette or perfume-bottle, consisting of a bottle-shaped body and a 30 bulged-form cork or stopper having the appearance of a cordage binding.

In testimony whereof I affix my signature in presence of witnesses.

HENRY F. H. BOTHE.
